UNITED STATES PATENT OFFICE.

PAUL PETRES, OF ASTORIA, NEW YORK.

DIRIGIBLE PROPELLER-MOUNTING.

1,271,213.

Specification of Letters Patent.

Patented July 2, 1918.

Application filed August 8, 1916, Serial No. 113,731. Renewed March 23, 1918. Serial No. 294,887.

To all whom it may concern:

Be it known that I, PAUL PETRES, a subject of the King of Hungary, and resident of Astoria, in the county of Queens and 5 State of New York, have invented new and useful Improvements in Dirigible Propeller-Mountings, of which the following is a specification.

This invention relates to improvements in 10 dirigible propeller mounting over my former invention, U. S. Patent #1,179,554, and has as its principal object the provision of means whereby the vanes or blades of the propeller may be directed so that the thrust 15 of the same may be at an angle with the axis of the driving shaft.

A second object is to provide such mountings in forms applicable to existing structures or new installations whereby the vessel 20 may be directed without the use of rudders or vanes, in either a horizontal or vertical course.

Another object is to provide means whereby the axis of the propeller may be manipulated at any desired angle from within the vessel and held in a rigid manner in its adjusted position by guides.

These and other objects, which will become more fully manifest as the disclosure 30 progresses, are attained by the novel construction and combination of parts hereafter described and shown in the accompanying drawings, forming a material part of this specification, and in which:—

35 Figure 1 is a fragmental top plan view of the propeller mounting, the vanes being shown in an angular position in broken lines.

Fig. 2 is a horizontal sectional view, taken on line 2—2 of Fig. 1.

40 Fig. 3 is a face plan view of the guard element in detail.

Fig. 4 is a fragmental sectional view, taken on line 4—4 of Fig. 3, and

Fig. 5 is a transverse sectional view, taken 45 on line 5—5 of Fig. 2.

In the drawings, a rigid support 10 is used as a mounting for the driving shaft 11, the latter having a collar 12 in front of the support, the shaft being engaged with a universal joint 13 comprised of crossing elements 15 and 16 respectively, the latter element being pivotally mounted in a yoke having arms 17, connected at the front by a rigid cross bar 18 and containing the rectangular hub 20 of 50 the propeller blades 21, the hub being held in position by means of the bolt 22, passing

through the arms 17 of the yoke and held rigidly therein by means of the nuts 24 as is clearly apparent in Fig. 2.

Formed with the bar 18 is an extending 55 hub 28 in which the shaft 29 is secured by means of a pin 30 or the like, whereby the shaft is caused to rotate. The extreme opposite end of the shaft is provided with a spherical element or ball 32, the same being seated in a slide 33 and held therein by means of the clamp nut 35 in a manner which prevents the ball from being withdrawn, but allows it to rotate freely within the bearing. 70

The slide 33 is suited to operate in guide-ways 40, and 42, arranged at right angles one to the other so that the slide may be moved either to the right or left, whereby the propeller vanes are similarly moved or so that the direction of the vessel may be diverted from a horizontal plane either up or down as may be desired, according to 75 whether the slide 33 is above or below the axis of the driving shaft 11. 80

In order that the slide 33 may be moved freely within the arcuate slot ways 40 and 42, the same are formed within a concave support 45, the center of which is rigidly mounted in register with the axis of the 85 driving shaft 11, the radius of the slots 40 and 42 being coincident with the distance between the center of the universal joint of the propeller mounting.

Means for diverting the slide 33 may be applied to the extending ends of the universal joint elements 15 and 16 or otherwise as may be preferred in a manner which will be obvious to those skilled in the art. 90

Thus it will be seen that a propeller 95 mounting has been disclosed which is capable of being directed in any preferred course so that a vessel, particularly of the airship type, may be guided and controlled as well as propelled and without the use of extraneous appliances, as rudders, vanes or the like. 100

Having thus described my invention, what I claim as new and desire to secure by Letters Patent is:—

1. In a dirigible propeller mounting, the combination with the propeller blades, a yoke therefor, and means for rotating said blades, of a universal joint interposed between said yoke and said driving means, a shaft extending from the said yoke oppositely from said driving means, a slide engaged with said shaft, and a guide for said 105 110

slide whereby it may be moved rectilinearly in either of two opposite paths as right angles one to another.

2. In a dirigible propeller mounting, the combination with the propeller, a support at the center thereof, a driving shaft for said support, a universal joint between said driving shaft and said support, an arm extending outwardly from said support normally to the axial plane of said driving shaft, a spherical end formed on said arm, a slide engaged with said spherical end, and arcuate guides rigidly mounted opposite to said yoke, and means formed on said arm operable within said arcuate guides whereby the angularity of the propeller blades may be controlled.

3. In a dirigible propeller mounting, the

combination with a propeller, a driving shaft therefor, a rigid support for said driving shaft, a yoke containing the hub of said propeller, universal joint connections between 20 said yoke and said driving shaft, an arm extending outward from said yoke perpendicular to the blades of said propeller, arcuate guides rigidly mounted opposite to said yoke, and means formed on said arm operable 25 within said arcuate guides whereby the angularity of the propeller blades may be controlled.

In testimony whereof I have signed my name to this specification.

PAUL PETRES.
